WRAP STRIPE ATTACHMENT FOR
KNITTING MACHINES

Benjamin H. Jordan, High Point, N. C.

Application August 6, 1951, Serial No. 240,459

6 Claims. (Cl. 66—135)

1

This invention relates to circular independent needle knitting machines and more especially to an improved demountable wrap stripe attachment therefor.

It is the primary object of this invention to provide an improvement in a circular knitting machine characterized by a wrap disk disposed above and in closely spaced relation to the horizontal plane of the upper ends of the needles in the needle circle, the axis of the disk being parallel to and eccentric to the axis of the needle circle and with means for rotating the disk at the same speed as that of the needle circle with the result that the disk presents the wrap yarn across the needle circle and back behind needles upon certain needles being raised above the normal horizontal plane of the upper ends of the needles thus causing said raised needles to engage the wrap yarns and resulting in wrapping the wrap yarns around the needles during knitting.

The improvement is particularly constructed to provide means for moving into position between the wrap disk and the upper ends of the needles to thus move the yarns or yarn extending between the wrap disk and the knitted fabric out of the path of travel of the raised needles, such action preferably being effected with movement of the gap closer to closed position thus obviating the necessity of moving or elevating the wrap disk during reciprocatory knitting or during any periods in which it may be desired to prevent the elevated needles from taking the wrap yarns.

It is another object of this invention to provide an improved means for supporting the wrap disk and the associated wrap head comprising a normally horizontally disposed bracket in which the shaft to which the lower end of the disk is secured is rotatably mounted and on which the bobbins for the wrap yarn and the usual tension means therefor are disposed and which bracket may be readily swung upwardly about a pivot to one side of the vertical plane of the knitting instrumentalities and having means on the bracket for limiting outward movement thereof upon the bracket being raised or swung upwardly to inoperative position to thus cause the shaft with the disk thereon and other parts of the wrap head to extend substantially radially of the needle cylinder although they may be swung upwardly and outwardly beyond the center of gravity of the wrap head and thus preventing the wrap head from swingably depending from the knitting machine which, heretofore, has resulted in the various parts of the wrap head being dam-

2

aged inadvertently by operators upon the operators repairing or adjusting the knitting machine.

Some of the objects of the invention having been stated, other objects will appear as the description proceeds when taken in connection with the accompanying drawings, in which—

Figure 1 is a front elevation of the upper portion of a circular knitting machine showing the improved wrap head and bracket for supporting the same in association therewith;

Figure 2 is an elevation looking at the left-hand side of Figure 1 with the upper portion of the machine broken away and illustrating portions of the machine which are disposed at a lower plane than that shown in Figure 1;

Figure 3 is a top plan view with parts in section taken substantially along the line 3—3 in Figure 1;

Figure 4 is an enlarged fragmentary vertical sectional view showing the manner in which the clamp and cutter plate is mounted;

Figure 5 is another enlarged vertical sectional view taken substantially along the line 5—5 in Figure 3 and showing the manner in which the wrap head is supported;

Figure 6 is a fragmentary vertical sectional view similar to the lower central portion of Figure 5 but showing the improved means for moving the wrap yarns out of the path of travel of the raised needles in an operative position;

Figure 7 is a fragmentary top plan view with parts in section looking down at the top of Figure 6.

Referring more specifically to the drawings, the numeral 10 broadly designates the frame of a circular knitting machine of the type employed for knitting men's socks and which comprises a bed plate 12 through which a driven needle cylinder 13 extends. This needle cylinder 13 is of usual construction and is driven by conventional means, not shown, in a counter-clockwise direction in Figure 3. The needle cylinder has a plurality of circularly arranged vertically movable independent latch needles generally designated at N mounted thereon, which needles are raised and lowered during rotation of the needle cylinder by conventional needle cams, such as the cam 14 in Figure 5, mounted on a cam ring 15 suitably secured to the bed plate 12.

As is well known to those familiar with the art, the means for driving the needle cylinder 13 also drives the wrap stripe mechanism through the medium of a vertically disposed shaft 17 which may be driven in a manner substantially as shown in the patent to C. S. Groves, Sr., et al, No.

2,451,673 of October 19, 1948. This shaft 17 is rotatably mounted in a bearing post 18 suitably secured, as by screws 20, to the upper surface of the bed plate 12. A further description of the manner in which the wrap head mechanism is driven will be provided later in this context.

The knitting machine also has a sinker head 21 which is supported in a conventional manner and which has conventional sinkers not shown, therein which cooperates with the needles in forming stitches. A conventional latch ring 22 is disposed above the needle cylinder and extends rearwardly and is pivotally mounted, as at 23, on a post 24 suitably secured, as by screws 25, to the upper surface of the bed plate 12. The latch ring has a forwardly projecting portion 22b integral therewith, the front end of which is supported on a conventional post 26. This post 26 is also suitably secured to the upper surface of the bed plate 12, as by screws 27.

The latch ring 22 has a throat gap 30 therein in which a plurality of conventional yarn feed fingers 28 operate in a conventional manner. The throat gap 30 is closed during reciprocatory knitting by a conventional gap closer 31 and which has a flanged segmental ring portion 32 integral therewith mounted for oscillatory movement in the latch ring 22 (Figures 3, 5, 6 and 7). The gap closer is held in normal operating position so as not to close the throat gap 30 during circular knitting by a tension spring 33 which is anchored at its front end (Figures 3 and 7) to a suitable spring anchor 34 secured to the exterior of the latch ring 22. The rear end of the tension spring 33 is connected to the upper end of a lever 35 to which a rod 36 is connected. This rod 36 extends forwardly and is pivotally connected to the ring portion 32 of the gap closer 31. In this instance, the front end of the rod 36 is bent downwardly and slidably penetrates the ring portion 32 and, therefore, the latch ring 22 has a groove 22a in the left-hand upper edge thereof to accommodate the downwardly bent end of the rod 36.

It will be observed in Figure 2 that the lever 35 extends downwardly and is pivotally mounted, as at 37, on the post 24 and has a heel portion 40 projecting forwardly therefrom. The lower surface of this heel portion 40 is engaged by the upper surface of an angle clip 41 suitably secured to a thrust rod 42, as by screws 43. The thrust rod 42 is guided in slotted guide members 45 and 46 which are a usual part of this type of knitting machine. The lower end of the thrust rod 42, at times, bears against a cam member 47 suitably secured to a main pattern drum 50 which is driven by conventional means, not shown. It is evident that, at times, the thrust rod 42 rests upon the upper peripheral surface of the main pattern drum 50 as shown in Figure 2.

The pattern drum 50 is also instrumental in controlling the movement of the conventional yarn feed fingers 28 but since the connections between the yarn feed fingers 28 and the pattern drum 50 are conventional, an illustration and description thereof is deemed unnecessary.

The pattern drum 50 also controls vertical movement of a thrust rod 51 disposed adjacent the thrust rod 42, only the upper portion of which is visible in Figure 2. The upper end of the thrust rod 51 engages the down-turned rear end of a lever 52 which is pivotally mounted, as at 53, on an upwardly projecting portion 54 integral with the latch ring 22. It will be observed in Figure 7 that this lever 52 extends forwardly and then

curves outwardly and again forwardly and is normally urged upwardly in Figure 2 by a tension spring 55 which is suitably connected at its lower end to the front end of the lever 52 and the upper end of which is connected to a rod 56.

The rod 56 extends forwardly and downwardly and is threadably embedded in a plate 57 (Figure 4) which is suitably secured, as by a screw 69 to the raised forwardly projecting portion 22b of the latch ring 22. The plate 57 projects inwardly above the segmental ring portion 32 of the gap closer 31 and beyond the inner surface of the latch ring 22 and supports a combination clamp and cutter plate and wrap horn broadly designated at 62.

It will be observed in Figure 5 that this plate 62 is of lesser diameter than the diameter of the needle circle so that the needles may move upwardly past the plate 62, this plate being disposed at a lower elevation than the throat gap 30 in the latch ring 22. The plate 62 is supported by the plate 57 through the medium of a vertically disposed rod 63 whose lower end is threadably embedded in the plate 62 and which projects upwardly and slidably penetrates the plate 57 and is suitably secured in a collar 64 which is, in turn, suitably secured, as by welding at 65, to the upper surface of the plate 57. This plate 62 may be of a type substantially shown in said Patent No. 2,451,673 or in the patent to Lawson et al., No. 1,872,760 of August 23, 1932.

The plate 62 is in the form of a disk and has an opening 70 therein which is shaped so as to provide an elongated, tapering, crescent-shaped finger or wrap horn 71 which extends about substantially one-half of the circumference of the needle circle at the inside thereof. This wrap horn 71 assists in wrapping the yarns to be knitted about the particular needles N which may be elevated by the cam 44 for taking the wrap yarn. It will be noted that the free end of the finger is spaced from the plate 62 to provide a passageway 72 (Figure 3) through which the wrap yarns pass as they are pulled over the wrap horn by downward movement of the needles (see Figures 5 and 6) with rotation of the needle cylinder in a counter-clockwise direction in Figure 3.

The passageway 72 is disposed at the knitting wave so the yarn may be pulled through the passageway 72 as the stitches are formed. However, in order to prevent the yarns from moving out of the opening 70, there is an angularly disposed guide member 74, which is shown in the form of a wire member, the lower end of which is welded to the wall of the opening 70 remote from the wrap horn 71 and which extends upwardly and outwardly and the free end of which is disposed adjacent and above the right-hand portion of the latch ring 22 as shown in Figures 3 and 5.

The clamp and cutter plate 62 supports a conventional clamping and cutting mechanism indicated generally at 75, this clamping and cutting mechanism 75 being provided for clamping and cutting the usual yarns which extend from the conventional yarn feed fingers 28. The free end of the lever 52 has a link 76 pivotally connected thereto and extending downwardly and inwardly therefrom at an angle and being pivotally connected, as at 77 (Figure 4), to a cutter blade 80 which is pivotally mounted in a block 81 which is a part of the clamping and cutting mechanism 75.

The block 81 is slidably penetrated by a pin 82 to which the blade 80 is fixed and a clamp blade

83 is fixed on the end of the pin 82 remote from the end on which the cutter blade 80 is secured. There are many types of clamping and cutting mechanisms which may be employed and a detailed description of its structure and mode of operation is deemed unnecessary. In fact, this clamping and cutting mechanism 75 may be identical to that shown in Figures 21 to 25, inclusive, in the patent to Lawson et al., No. 1,702,608 of February 19, 1929.

Wrap stripe mechanism and improved mounting therefor

The wrap stripe attachment or wrap head is broadly designated at 90 and comprises a vertically disposed wrap shaft 91 (Figures 1 and 5) provided with an enlarged upper end 92, a reduced intermediate portion 93 and a reduced lower end portion 94 of lesser diameter than the intermediate portion 93. The reduced intermediate portion 93 of the shaft 91 slidably penetrates a bushing 95 in which the portion 93 of the shaft 91 is keyed as at 96. The bushing 95 is journaled in an improved bracket designated broadly at 97 and which bracket constitutes the primary element of the improved mounting for the wrap head 90.

The bracket 97 has an upstanding boss portion 100 integral therewith which is provided with an enlarged bore 101 therethrough which is of substantially greater internal diameter than the external diameter of the bushing 95. The bracket 97 is also provided with axially aligned annular recesses 102 and 103 at the respective upper and lower surfaces thereof, the recess 102 being formed in the upper end of the enlarged or raised boss portion 100 of the bracket 97. These recesses 102 and 103 have the outer races of respective antifriction or ball bearings 104 and 105 mounted therein and preferably being secured therein by a pressed fit. These anti-friction or ball bearings 104 and 105 are preferably of the sealed type of bearing which is usually packed with a suitable lubricant before it is sealed thus obviating the necessity of lubricating the bearings 103 and 104.

The inner races of the ball bearings 103 and 104 preferably snugly encircle the bushing 95 and the bushing 95 is provided with a flange 95a at the upper end thereof in Figure 5 which rests against the upper surface of the inner race of the ball bearing 104 for supporting the bushing 95 and the associated parts of the wrap stripe mechanism 90.

The flange 95a of the bushing 95 abuts against the annular shoulder formed by the enlarged shaft portion 92 and also abuts against the central portion of a yarn carrier plate 107 which is centrally mounted on the lower end of the portion 92 of the shaft 91.

The bushing 95 has a plurality of closely spaced circularly arranged passageways or bores extending longitudinally therethrough and the yarn carrier plate 107 is suitably secured to the upper surface of the flange portion 95a of the bushing 95 as by screws 111. Therefore, the yarn carrier plate 107 is provided with a plurality of circularly spaced tubular yarn guides 112 which coincide with the bores or passageways 110 in the bushing 95 and, thus, the yarn carrier plate 107, and the yarn guides 112 rotate simultaneously with the bushing 95 and the shaft 91, the shaft 91 being driven in a manner to be presently described.

The yarn carrier plate 107 has a plurality of

upstanding stub shaft elements 113 fixed on the upper surface thereof, upon each of which is adapted to be mounted a corresponding bobbin 114 containing wrap yarn Y which is directed to the needles in a manner to be presently described.

The wrap yarn Y is withdrawn from each of the bobbins 114 initially upwardly through a yarn controlling and tensioning mechanism broadly designated at 115 and which is of usual construction and a detailed description of which is deemed unnecessary.

The yarn controlling and tensioning mechanism is mounted on a plate 116 fixed on a collar 117 which is secured to the enlarged portion of the shaft 91 substantially above the yarn carrier plate 107. The yarn, after passing through the controlling and tensioning mechanism 115, passes downwardly through guide tubes 120 which extend through the plate 116 and the collar 117. The yarn Y then extends downwardly through the tubular yarn guides 112 and the corresponding bores 110 in the bushing 95.

It will be observed in Figures 1 and 5 that the intermediate reduced portion 93 of the shaft 91 has a beveled gear 121 adjustably secured thereon, by any suitable means such as a set screw 122, this gear 121 being spaced substantially below the lower end of the bushing 95. The beveled gear 121 is also penetrated by a plurality of circularly spaced tubular yarn guides 123 which are disposed in alignment with the bores 110 in the bushing 95 and through which the wrap yarns Y extend.

The beveled gear 121 meshes with a beveled gear 125 fixed on the inner end of a horizontally disposed shaft 126 which is rotatably mounted in bearing portions or projections 130 and 131 which are spaced longitudinally of and depend from an arm 132 integral with the improved bracket 97. The shaft 126 also has a beveled gear 133 fixedly mounted thereon between the projections 130 and 131 depending from the arm 132 and this arm 132 is also provided with a hood portion defining an opening 134 within which the beveled gear 133 is disposed.

This beveled gear 133, in turn, meshes with a beveled gear 135 which is fixedly mounted on the upper end of the vertically disposed driven shaft 17 heretofore described and which gear 135 rotates in sliding engagement with the upper end of the post 18. Disposed in substantially horizontal alignment with the arm 132 but on the opposite side of the enlarged raised boss portion 100, is an arm 140, the outer end of which has an off-set or downwardly projecting portion 141 integral therewith.

The portion 141 is pivotally mounted, as at 142, in a corresponding bifurcated off-set or inwardly projecting portion 143 integral with the upper end of a post 144. The post 144 extends downwardly and is suitably secured, as by screws 145, to the upper surface of the bed plate 12 of the frame 10.

It will be observed in Figure 2 that the post 144 is provided with an opening 146 therein which is merely provided to reduce the weight of the post 144. However, the upper end of the post 144 is bifurcated adjacent the off-set portion 143 thereon to form a groove whose bottom is defined at 150 and the off-set portion 141 may have pivotal movement in the groove whose bottom is indicated at 150.

It is thus seen that the bracket 97 may be swung upwardly in a counter-clockwise direction in Figure 1 until the outer end of the arm 140 of the

bracket 97 rests against the bottom 150 of the groove in the upper end of the post 144 as shown in broken lines in Figure 1. The surface 150 will then prevent the bracket 97 from moving beyond this point although the center of gravity of the wrap head 90 is then disposed substantially outwardly of the vertical plane of the post 144.

It will be observed in Figure 1 that the post 18 has a lateral projection 152 integral therewith which is threadably penetrated by a set screw 153, this set screw 153 being held in adjusted position by a lock nut 154. The upper end of the set screw is engaged by the lower surface of the projection 131 integral with the arm 132 of the bracket 97 when the bracket 97 is in an operative position.

This insures that the gears 121 and 125 and 133 and 135 may be properly enmeshed during operation of the wrap head 90. The outer end of the projection 131 on the arm 132 of the bracket 97 has a leaf spring member 155 suitably secured thereto, as by a screw 156, which projects downwardly and is biased inwardly and is penetrated by a latch portion 157 projecting laterally from the free end of the laterally projecting portion 152 on the post 18 when the bracket 97 assumes an operative position. This insures that the bracket 97 may not be moved upwardly inadvertently. It is evident, however, that the lower end of the leaf spring member 155 may be biased outwardly by an operator when the operator desires to raise the bracket 97 and the corresponding wrap head 90 to inoperative position, such as during knitting wherein the wrap stripe attachment is not employed. It will be noted that when the bracket 97 and the corresponding wrap stripe attachment 90 are in the operative position shown in Figures 1, 3, 5, 6 and 7, the vertically disposed shaft 91 is disposed parallel to but eccentric of the axis of the needle cylinder 13.

A wrap disk 160 is fixedly mounted on the reduced lower portion 94 of the wrap shaft 91 (Figures 5 and 6) by any suitable means such as a set screw 161. This wrap disk has a plurality of circularly spaced vertically disposed passageways 162 therein through which the wrap yarns pass in their downward travel to the needles. The lower surface of the wrap disk 160 is disposed above but in closely spaced relation to the segmental ring portion 32 of the gap closer 31 and, upon rotation of the wrap disk 160, the passageways 162 therein move across the needle circle, because the wrap shaft 91 is mounted eccentrically with respect to the center of the needle circle although its vertical axis is at a point within the needle circle.

Thus during normal operation of the wrap stripe attachment 90, the yarn is fed from the wrap disk 160 downwardly and inwardly at an angle from adjacent the upper surface of the ring portion 32 of the gap closer 31 from whence the wrap yarns pass downwardly and through the opening 70 in the combination clamp and cutter plate 62, the stitches being formed below the horizontal plane of the clamp and cutter plate 62. Thus, upon any needles being elevated, by the cam 14, to the position of the needle shown at the right-hand side of Figures 5 and 6, the yarn from the adjacent passageway 162 in the wrap disk 160 will be taken in the hooks of the needles and will subsequently be wrapped around the needles in a well known manner in advance of the needles passing through the usual stitch cams, not shown, to form

stitches therefrom. On the other hand, there are certain times during which it may be desired that the wrap stripe attachment 90 remains in an operative position, such as during the knitting of the heel pocket and the toe pocket, which occurs during reciprocatory knitting, although it is not desirable that the raised needles take the wrap yarn from the wrap disk 160.

During reciprocatory knitting, such as in knitting the heel pocket and toe pocket of a stocking, and possibly at other times during circular knitting, it may be desirable to continue elevating the needles as they move adjacent the position shown in the right-hand portion of Figures 6 and 7 although it may not be desirable that the wrap yarn be taken in the hooks of these particular elevated needles. Therefore, I have provided an improved means for preventing the elevated needles from taking the yarn from the wrap disk 160 which comprises a wrap yarn deflector finger 165 which rests against the upper surface of the ring portion 32 of the gap closer 31 and has sliding engagement therewith.

This finger 165 is disposed between the lower surface of the outer portion of the wrap disk 160 and the corresponding upper surface of the ring portion 32 of the gap closer 31 but is normally out of the path of travel of the wrap yarns Y as they move past this point as is clearly shown in Figure 5. This finger 165 extends forwardly and is pivotally mounted, as at 166, on the upper surface of an angle clip 167 suitably secured, as by a screw 172 (Figure 7), to the conventional forwardly projecting portion 22b integral with the latch ring 22, which portion 22b rests atop the upper surface of the post 26 and is resiliently held in engagement therewith by a conventional leaf spring member 171.

The wrap yarn deflector finger 165 is normally urged inwardly towards the needle circle by a tension spring 173 which is connected at one end thereof (Figure 7) to the finger 165 rearwardly of the pivot point 166. The other end of the tension spring 173 is connected to the screw 172 which secures the finger support 167 to the forwardly projecting portion 22b of the latch ring 22. In order to bias the wrap yarn deflector finger 165 to the inoperative position shown in Figures 3 and 5 during periods in which the wrap yarns shall be taken in the hooks of the particular needles elevated to the position of the needles shown at the right-hand side of Figures 5 and 6, the ring portion 32 of the gap closer 31 has an abutment 175 projecting upwardly therefrom which is shown in the form of a screw in Figures 3 and 7.

The wrap yarn deflector finger 165 is provided with a notch 176 on the inner edge thereof, the bottom of which is engaged by the abutment 175 when the gap closer 31 is in the operative position shown in Figures 3 and 5. Thus, whenever the gap closer 31 is not extending across the gap 30, the wrap yarn deflector finger 165 is held in an inoperative position by the abutment 175. On the other hand, upon the cam 47 in Figure 2 on the main pattern drum 50 moving into engagement with the lower end of the thrust rod 42, the thrust rod 42 is elevated to cause the lever 35 to move in a counterclockwise direction thus moving the rod 36 rearwardly and thereby causing the gap closer 31 to move in a clockwise direction in Figure 3 or from the position shown in Figure 5 to the position shown in Figure 6.

It is evident that this will cause the abutment 175 to move from right to left or from the

position shown in Figure 3 to the position shown in Figure 7 with the result that the wrap yarn deflector finger 165 will move inwardly from the position shown in Figures 3 and 5 until the rear end thereof engages the upwardly projecting portion 54 of the latch ring 22 to thus limit its inward movement upon the abutment 175 moving out of engagement with the notch 176 in the finger 165. The plate 57 is cut away to form a recess 177 therein to accommodate the abutment 175 as it moves from the position shown in Figure 3 to the position shown in Figure 7.

Now, as the finger 165 moves inwardly in the manner heretofore described, the medial portion thereof assumes substantially the position shown in Figure 6, immediately above the corresponding portion of the needle circle, and, in so doing, the inner edge of the wrap yarn deflector finger 165 engages the wrap yarns extending through the passageways 162 in the outer portion of the wrap disk 160 thus deflecting these wrap yarns out of their normal path of travel and causing the wrap yarns to be moved out of the path of travel of any needles which may be elevated to the position in which they normally take the wrap yarns as they move beneath the wrap disk 160.

It is thus seen that, although some of the needles N may be elevated to where the hooks thereof would ordinarily take the wrap yarns from the corresponding passageways 162 in the wrap disk 160, the wrap yarns will have then moved inwardly of the path of travel of these needles with the result that they will fail to take the wrap yarns and will thus subsequently pass through the stitch cams to form stitches from the usual body yarns only, not shown, which are fed through the conventional yarn feed fingers 29.

It is thus seen that I have provided an improved bracket for supporting the wrap stripe attachment 90 and improved means for deflecting the wrap yarns out of their normal path of travel as they are directed from the wrap disk 160 through the opening 70 in the plate 62 and with the result that it is not necessary to move the wrap stripe attachment 90 to inoperative position manually during knitting in which it is desired that the wrap yarns are not knitted into the fabric. Moreover, the particular action of this wrap yarn deflector finger 165 obviates the necessity of elevating the wrap disk 160 as has heretofore been necessary thus eliminating a plurality of complicated parts which have heretofore been required, including specially arranged cams on the main pattern drum.

In the drawings and specification, there has been set forth a preferred embodiment of the invention and although specific terms are employed, they are used in a generic and descriptive sense only and not for purposes of limitation, the scope of the invention being defined in the claims.

I claim:

1. In a circular knitting machine having a needle circle and also having a latch ring provided with a gap throat therein in which a plurality of yarn feed fingers are normally disposed and also having a gap closer and means for moving the gap closer into and out of position for closing and opening the throat gap, said machine also having a frame and also having a wrap stripe attachment including a driven rotatable disk disposed closely adjacent the upper surface of the latch ring and being fixed on the lower end

of a driven vertically disposed wrap shaft whose axis is disposed in a vertical plane and to one side of the axis of the needle circle, said machine also having means for feeding wrap yarns to the wrap disk and also having means for raising certain of the needles to take the wrap yarns from the wrap disk, a pattern controlled deflector finger disposed in a horizontal plane between the lower surface of the wrap disk and the upper surface of the latch ring and movable in a horizontal plane for selectively deflecting the wrap yarns which normally extend from the wrap disk to the needles inwardly to cause the needles to clear the wrap yarns as they move adjacent the wrap disk.

2. In a circular knitting machine having a needle cylinder provided with a plurality of circularly arranged vertically reciprocable hooked needles and also having means for elevating certain of the needles at a predetermined point, said machine also having a wrap stripe attachment provided with a driven rotatable wrap disk disposed closely adjacent the hooks of said elevated needles, the axis of the wrap disk being disposed in a vertical plane and to one side of the axis of the needle cylinder, said machine also having means for feeding wrap yarns to the wrap disk whereby said raised needles may take the yarn from the wrap disk, a movable pattern controlled deflector finger for deflecting the wrap yarns out of their normal path of travel from the wrap disk to the needles at predetermined intervals while maintaining the wrap disk in its position closely adjacent the hooks of the elevated needles to thereby prevent the yarns from being taken in the hooks of the needles at said predetermined intervals.

3. In a circular knitting machine having a needle circle including hooked needles, said machine also having a latch ring provided with a gap throat therein in which a plurality of yarn feed fingers are disposed and also having a gap closer and means for moving the gap closer into and out of position for closing and opening the throat gap, said machine also having a wrap stripe attachment including a driven rotatable disk disposed closely adjacent the upper surface of the latch ring with the axis of the wrap disk being disposed in a vertical plane and to one side of the axis of the needle circle, said machine also having means for feeding wrap yarns to the wrap disk and also having means for raising some of the needles to take the wrap yarns from the wrap disk, the combination of means for deflecting the wrap yarns out of their normal path of travel from the wrap disk to the needles comprising a wrap yarn deflector finger disposed between the lower surface of the wrap disk and the upper surface of the latch ring, means controlled by movement of the gap closer to a position closing said throat gap for moving the wrap yarn deflector finger inwardly substantially towards the axis of the needle circle, whereby the wrap yarn deflector finger engages the wrap yarns extending from the wrap disk and moves the same inwardly of the hooks in the corresponding needles to prevent the yarn from being taken by the needles, and means controlled by movement of the gap closer to a position away from the throat gap for moving the wrap yarn deflector finger out of the path of the wrap yarns extending from the wrap disk to thereby permit the wrap yarns to be taken by the needles.

4. In a structure according to claim 3, said gap

closer having a segmental ring portion thereon mounted for sliding movement on said latch ring, said deflector finger being disposed immediately above the segmental ring portion of the gap closer, an abutment projecting upwardly from said segmental ring portion and spring means urging said deflector finger toward the abutment whereby, upon movement of said gap closer with its ring portion in either direction, the deflector finger will move therewith in engagement with said abutment thereby controlling the position of the deflector finger in accordance with the position of the gap closer.

5. In a circular knitting machine having a needle circle including hooked needles, said machine also having a latch ring provided with a gap throat therein in which a plurality of yarn feed fingers are disposed and also having a gap closer and means for moving the gap closer into and out of position for closing and opening the 10 throat gap, said machine also having a wrap stripe attachment including a driven rotatable disk disposed closely adjacent the upper surface of the latch ring with the axis of the wrap disk being disposed in a vertical plane and to one side of the axis of the needle circle, said machine also having means for feeding wrap yarns to the wrap disk and also having means for raising some of the needles to take the wrap yarns from the wrap disk, the combination of means for deflecting the wrap yarns out of their normal path of travel from the wrap disk to the needles comprising a wrap yarn deflector finger disposed between the lower surface of the wrap disk and the upper surface of the latch ring, means controlled by movement of the gap closer to a position closing said throat gap for moving the wrap yarn deflector finger inwardly substantially towards the axis of the needle circle, and means controlled by movement of the gap closer to a position away from the throat gap for moving the wrap yarn deflector finger out of the path of the

wrap yarns extending from the wrap disk to thereby permit the wrap yarns to be taken by the needles.

6. In a circular knitting machine having a needle circle including hooked needles, said machine also having a latch ring provided with a gap throat therein in which a plurality of yarn feed fingers are disposed and also having a gap closer and means for moving the gap closer into and out of position for closing and opening the throat gap, said machine also having a wrap stripe attachment including a driven rotatable disk disposed closely adjacent the upper surface of the latch ring with the axis of the wrap disk being disposed in a vertical plane and to one side of the axis of the needle circle, said machine also having means for feeding wrap yarns to the wrap disk and also having means for raising some of the needles to take the wrap yarns from the wrap disk, the combination of means for deflecting the wrap yarns out of their normal path of travel from the wrap disk to the needles comprising a wrap yarn deflector finger disposed between the lower surface of the wrap disk and the upper surface of the latch ring and means controlled by movement of the gap closer to a position closing said throat gap for moving the wrap yarn deflector finger inwardly substantially towards the axis of the needle circle.
